LUBRICATING DEVICE

Hans Kreidel, Wiesbaden, Germany

Application February 16, 1933, Serial No. 656,993

10 Claims. (Cl. 184—27)

The invention relates to a lubricating device containing a suction and pressure pump for the purpose of periodically and automatically feeding an exactly metered quantity of oil under high pressure to lubricating lines or parts to be lubricated. The lubricating device in this way adapts itself particularly well for the lubrication of running chains as well as for the purpose of feeding oil to high pressure lines such as they are, for example, employed in connection with central lubricating devices. In contra-distinction to the lubricating devices that are in use for similar purposes, the present invention provides a simple construction in which complicated arrangements and sensitive distributing elements such as valves and the like are avoided. The device requires very little power for its operation and may be made to function reliably and accurately even in the smallest embodiments. The pump of the lubricating device of the present invention has a low speed lubricant suction stroke and a rapid lubricant discharge stroke.

The drawing shows one of many possible embodiments of the invention.

Fig. 1 is a vertical section through the lubricating device.

Fig. 2 is a vertical sectional view taken on the line 2—2 of Figure 1.

Fig. 3 shows a section of some details of the pump drive taken on the line 3—3 of Figure 1 and

Fig. 4 is a fragmentary elevation of the bearing parts of the suction and pressure pump, the parts arranged in front of it having been omitted.

The oil reservoir comprises a side wall 1 having a rib or wall 2 fitted perpendicularly to it, and a cover 3, these parts being united to one another in oil-tight engagement by means of a number of screws 4. 5 denotes the filler plug. A pivot 6 is screwed into the wall 2 and is located in the reservoir in as low a position as possible. This pivot 6 is provided with two adjoining channels, a suction channel 7 and a feeding channel 8 which latter is led through the side wall of the reservoir to the exterior thereof. A pump cylinder 9 has an annular eye part 10 and is with this annular eye part 10 so mounted on the pivot 6 that it is able to swivel transversely. The suction channel 7 extends through the pivot 6 while the feeding channel 8 is elbow-shaped, passing only half way through the pivot and extending longitudinally through the pivot and passing through the wall 2 and the side wall 1 to the exterior. The suction channel 7 has thus two openings on the surface of the pivot 6 while the feeding channel 8 has only one.

An opening provided in the bottom of the pump cylinder 9 is able to register with the two adjoining openings of the channels 7 and 8 as the pump cylinder swivels around the pivot 6. The interior of the pump cylinder 9 may in this way intermittently communicate with the suction channel 7 or with the feeding channel 8 (Fig. 1). 11 denotes an opening in the annular eye part 10 of the pump cylinder 9 and has for its purpose to ensure a free communication of the oil channel 7 with the interior of the oil reservoir during all possible angular positions of the pump cylinder. Two discs 12 are united by means of the pins 13 which are loosely fitted on the pivot 6 so that they may move around it. 15 A ring 15 made of spring wire is fitted into a groove of the pivot 6 and prevents axial displacement of the annular eye part 10 of the pump cylinder and of the two discs 12. The upper end of a plunger 16 which is reciprocable in the pump cylinder is connected to a gudgeon pin 18 on the feed wheel 17 which is rotatable on the axle 20. The upper end of the plunger or connecting rod 16 is fitted with transverse rods 19. Coiled springs 14 each have one end secured to one of these transverse rods 19 and the other end to the pins 13. Rotation of the wheel 17 in the direction of the arrow in Fig. 1, causing the gudgeon pin 18 of the plunger 16 to describe a circular path, not only brings about a displacement 20 of the plunger 16 in the pump cylinder 9 and a successive tensioning and release of the springs 14, but also causes the pump cylinder 9 with its annular eye part 10 to oscillate about the pivot 6 in such a way that during the ascending motion 25 of the plunger 16 (suction stroke) the interior of the pump cylinder 9 communicates with the suction channel 7 and thereby with the interior of the oil reservoir, while during the descending motion of the plunger 16 (compression stroke), 30 the interior of the pump cylinder 9 communicates with the feeding channel 8 and thereby with the pressure line that leads to the exterior. A position of feed is indicated in Fig. 1 by dotted lines, the gudgeon pin 18 being in this case in 35 position 18a.

The feed wheel 17 which is located on the axle 20 is toothed over somewhat more than half of its circumference and is rotated through the action of the feed lever 21 and the pawl 22. It 40 is necessary that both the feed lever 21 and the pawl 22 be pressed against the circumference of the feed wheel 17 during action, and this pressing of the said parts against the circumference of the feed wheel 17 can be accomplished in dif- 45 50 55

ferent ways. The pawl 22 has two arms and is mounted on the pin 24, the pawl being held to the wheel 17 by spring 23. The feed lever 21 likewise has two arms which together form a bell 5 crank lever. Its free arm carries a float 30 which, displacing lubricant contained in the reservoir, presses the feed lever 21 against the circumference of the feed wheel 17. The feed lever 21 itself is appropriately mounted on an eccentric 10 25 of a worm wheel 26 which is rotatable upon the axle 27. The worm wheel 26 is driven by a worm 28 which is in mesh with it and is secured to or formed integrally with a shaft 29 that projects through the side wall 1 to the exterior. 15 The shaft 29 is journaled in the said side wall 1 and in an angular bearing part fitted to the wall 2, and may be driven by any suitable means. Rotation of the worm wheel 26 imparts a reciprocatory feed motion to the feed lever 21 because 20 of the action of the eccentric 25 upon which it is mounted. This feed motion of the feed lever 21 causes slow rotation of the feed wheel 17. The stroke of the feed lever 21 is amply sufficient to rotate the feed wheel 17 through an angle 25 corresponding to the pitch of the ratchet teeth thereon, and when thus advanced the feed wheel is restrained from return movement by the pawl 22. The feed wheel 17 is toothed over somewhat more than half of its circumference. Rotation 30 of the feed wheel 17 causes the plunger 16 to be raised so as to suck a quantity of the lubricant into the suction channel and into the pump cylinder. The springs are thus placed under tension and the pump cylinder 9 swivels in such a manner as to move its suction opening 35 slowly away from the suction channel 7. In the meantime, a quantity of the lubricant is drawn into the pump cylinder. The tensioned springs 14 will then be released as soon as the gudgeon 40 pin 18 has passed its upper dead center during the rotation of the feed wheel 17 and this causes the plunger 16 to be jerked back into the pump cylinder 9. During the downward or discharge stroke of the plunger the opening in the feed channel 8 in the pivot 6 registers with the lower 45 opening of the pump cylinder, and the quantity of the lubricant that previously has been sucked into the pump cylinder is fed to a lubricating line or to the part to be lubricated. The speed 50 at which the plunger 16 jerks back into the pump cylinder is dependent upon the strength and the tension of the springs 14, upon the diameter of the said plunger 16 and upon the viscosity of the lubricant so that different lubricant feeding 55 speeds may be obtained by the alteration of one or more of these factors. During the generally rapid discharge stroke of the plunger 16 into the pump cylinder, the non-toothed part of the feed wheel 17 glides over the feed lever 21 and the 60 pawl 22, and the feed mechanism of the feed wheel 17 will be out of action during this period. The action of the feed mechanism of the feed wheels will recommence as soon as the gudgeon pin 18 of the connecting rod passes its lower dead 65 center, since only then will the feed lever 21 and the pawl 22 mesh again with the toothed part of the feed wheel 17. A pressure of the lubricant or oil to be fed in excess of that allowed for by the tension of the springs 14 is prevented by 70 disengaging the feed mechanism for the feed wheel 17 during the discharge stroke of the plunger. Since the springs 14 are attached to the pins 13 of the discs 12 that are loosely fitted on to the pivot 6, the springs always remain in a 75 position parallel to the pump cylinders 9 and

thereby keep the latter tightly pressed against the surface of the pivot 6 during the discharge stroke of the plunger. This ensures an efficient seal between the pivot 6 and the pump cylinder 9 as the latter swivels about the former. Wear of the annular eye part 10 that might occur in the course of time could not disadvantageously influence the operation of the lubricating device inasmuch as the lower part of the pump cylinder that is provided with the oil inlet and outlet opening is pressed tightly against the surface of the pivot 6 throughout the discharge stroke. 10

In centralized lubricating systems it is highly desirable to maintain the conduits completely filled with oil, and it is therefore necessary to provide means for preventing the discharge of air into the conduits by the pumping mechanism. Unless such means were provided in the device of the present invention, the pump would deliver air to the conduit system when the level of the oil in the reservoir dropped below the inlet port 11. In the present invention, this inconvenience has been overcome by the provision of a float 30 that is carried on an arm of the bell crank feed lever 21, and that, at a certain level of the lubricant in the reservoir automatically throws the pump out of commission. As long as the level of the lubricant in the reservoir is of a sufficient height, the float 30 will be raised through the buoyant action of the lubricant and the feed lever 21 will thus be sufficiently pressed against the circumference of the feed wheel 17. However, should the level of the lubricant in the reservoir drop below a certain limit, the float 30 would likewise drop so that the feed lever 21 would no longer be pressed against the circumference of the feed wheel 17, and thereby interrupt the rotation of this latter. 30

The invention may be embodied in various forms and changes may be made in the drive for the pump plunger. For example, the disc 17 may 40 be secured to its shaft 20 and the latter extend outwardly from the reservoir to be driven by any suitable source of power. Numerous other changes may be made without departing from the basic features of my invention defined in the following claims. 45

Having thus described the invention, what I claim as new and desire to secure by Letters Patent is:

1. A lubricating device comprising an oil reservoir with a filler spout; a therein rigidly mounted pivot located in a position as low as possible therein and having a suction channel and a feeding channel with openings at the surface of the pivot the one of which is in communication with the oil reservoir and the other with a pressure feed line that extends to the exterior, a pump cylinder fitted with an annular eye part by which it is so attached to the said pivot that it may swivel around it, an aperture in the cylinder bottom that is so arranged as to register with the openings of the suction channel that passes through the pivot and the feeding channel, a plunger moving in the pump cylinder, this plunger with its connecting rod top end being attached to a gudgeon pin secured to a rotating wheel that is fitted to an axle, the wheel being toothed over a portion of its circumference, a feed lever that engages with the teeth of the wheel and is pressed against them, this feed lever being attached to a rotating eccentric by the aid of which it receives its feeding motion. 55

2. A lubricating device comprising an oil reservoir with a filler spout; a therein rigidly mounted pivot located in a position as low as possible 70

therein and having a suction channel and a feeding channel with openings at the surface of the pivot the one of which is in communication with the oil reservoir and the other with a pressure feed line that extends to the exterior; a pump cylinder fitted with an annular eye part by which it is so attached to the said pivot that it may swivel around it; an aperture in the cylinder bottom that is so arranged as to register with the openings of the suction channel that passes through the pivot and the feeding channel; a plunger moving in the pump cylinder, this plunger with its connecting rod top end being attached to a gudgeon pin secured to a rotating wheel that is fitted to an axle, the wheel being toothed over a portion only of its circumference; a feed lever that engages with the teeth of the wheel and is pressed against them, this feed lever being attached to a rotating eccentric by the aid of which it receives its feeding motion; and a pawl that, under the action of a spring, engages with the teeth of the said wheel for the purpose of preventing a return motion of this wheel.

3. A lubricating device comprising an oil reservoir with a filler spout; a therein rigidly mounted pivot located in a position as low as possible therein and having a suction channel and a feeding channel with openings at the surface of the pivot the one of which is in communication with the oil reservoir and the other with a pressure feed line that extends to the exterior; a pump cylinder fitted with an annular eye part by which it is so attached to the said pivot that it may swivel around it; an aperture in the cylinder bottom that is so arranged as to register with the openings of the suction channel that passes through the pivot and the feeding channel; a plunger moving in the pump cylinder; this plunger with its connecting rod top end being attached to a gudgeon pin secured to a rotating wheel that is fitted to an axle, the wheel being toothed over a portion of its circumference; a feed lever that engages with the teeth of the wheel and is pressed against them, this feed lever being attached to an eccentric by the aid of which it receives its feeding motion; and a pawl that, under the action of a spring, engages with the teeth of the said wheel for the purpose of preventing a return motion of this wheel, a shaft on to which the eccentric that serves to communicate the feeding motion to the feed lever, a worm wheel on said shaft, and a worm meshing with the said worm wheel and being seated on a shaft that extends out of the oil reservoir.

5. A lubricating device comprising an oil reservoir with a filler spout; a therein rigidly mounted pivot located in a position as low as possible therein and having a suction channel and a feeding channel with openings at the surface of the pivot the one of which is in communication with the oil reservoir and the other with a pressure feed line that extends to the exterior; a pump cylinder fitted with an annular eye part by which it is so attached to the said pivot that it may swivel around it; an aperture in the cylinder bottom that is so arranged as to register with the openings of the suction channel that passes through the pivot and the feeding channel; a plunger moving in the pump cylinder, a rotating toothed drive wheel, a gudgeon pin carried thereby and forming part of a pivotal connection between said toothed wheel and said plunger, a feed lever that engages with the teeth of the wheel and is pressed against them, an eccentric for imparting a feeding motion to said feed lever, a spring pressed pawl engageable with the teeth of the said wheel for the purpose of preventing a return motion of this wheel, a worm wheel for rotating said eccentric, a worm meshing with the said worm wheel, a shaft carrying said worm and extending out of the oil reservoir, said drive wheel being toothed only over somewhat more than half of its circumference, the other part of the wheel having a smooth circular peripheral edge, coiled springs each having one end attached to the connecting rod top end and its other end attached to the pivot of the pump cylinder, said feed lever being in the form of a bell crank lever and having a float attached to it the buoyancy of the float causing the teeth of the feed lever to be pressed against the periphery of the wheel.

6. Lubricating device in accordance with claim 4, thereby characterized that the springs which with their one end are attached to the connecting rod top end are, with their other end, attached to specially provided discs that are loosely fitted on the pivot of the pump cylinder.

7. In a pump for centralized lubricating systems, the combination of a cylinder, a plunger reciprocable therein, resilient means for actuating said plunger upon its discharge stroke, a ratchet wheel having a part operative to actuate said plunger throughout its suction stroke, a pawl engageable with said ratchet wheel, and a buoyant element for holding said pawl in cooperative engagement with said ratchet wheel.

8. In a pump and reservoir installation for centralized lubricating systems, the combination of a lubricant reservoir, a pump having an inlet port adjacent the bottom of said reservoir, a disengageable mechanism comprising a pawl and ratchet for operating said pump, and means controlled by the level of the lubricant in said reservoir to hold said pawl in operative engagement with said ratchet as long as the lubricant level is above a predetermined minimum.

9. In a force feed lubricator, the combination

of a reservoir, a pivot stud secured thereto adjacent the bottom thereof, said stud having inlet and discharge passageways, a cylinder having a sleeve surrounding said stud, said cylinder having a port registerable alternately with the ends of said passageways respectively upon oscillation of said cylinder about said stud, a plunger in said cylinder, rotating means pivotally connected to said plunger for withdrawing the plunger from said cylinder, and a plurality of springs for forcing said plunger into said cylinder, each of said springs having one end secured to said plunger and the other end pivotally secured to said stud.

10. In a force feed lubricator, the combination

of a reservoir, a plunger pump in said reservoir, resilient means for actuating said pump upon the discharge stroke thereof, a crank disk having a crank pin pivotally connected to the plunger of said pump, said disk having ratchet teeth formed in a portion only of the periphery thereof, an eccentric, means for rotating said eccentric, a pawl mounted upon said eccentric to be oscillated thereby, and a float connected to said pawl and operative to maintain the latter in position for engagement with said ratchet teeth on said disk as long as a predetermined quantity of lubricant is maintained within said reservoir.

HANS KREIDEL.
